UNITED STATES PATENT OFFICE.

WALENTY FILA, OF EDWARDSVILLE, PENNSYLVANIA.

PROPELLUTION DEVICE FOR SHIPS.

Application filed June 9, 1927. Serial No. 197,614.

This invention relates to a new and useful device in the nature of a propulsion device for boats, operated by an internal combustion motor.

- 5 The object of the invention is to provide a propulsion device of novel construction and arrangement of parts hereinafter more fully described, claimed and illustrated in the accompanying drawing.
- 10 Fig. 1 is a top plan view of my improved propulsion device.

Fig. 2 is a transverse sectional view taken on the line 2—2 of Fig. 1.

Fig. 3 is a side elevational view thereof.

- 15 Fig. 4 is a top plan view of a boat equipped with my improved device.

Fig. 5 is a side elevational view thereof.

As here embodied my improved device comprises a lazy tong consisting of a plurality of bars 10 and 11 crossing each other centrally and pivoted, as at 11. The bars 10 and 11 are formed or bent curved, as clearly shown in Fig. 1. The bars 10 and 11 are pivotally secured to each other as at 12. The 25 lazy tong is pivotally attached, at its center as at 13, at one side thereof, adjacent to the base 14, to the bracket 15 secured to and extended from the said base. The lazy tong is pivotally attached, at its center, opposite the bracket 15, by the pin 16, provided with an enlarged head, to which is pivotally attached, as at 17, the rod 18. The rod 18 is pivotally attached, at its other extremity, to the eccentric pin 19, secured to the rim of the fly wheel 20, of an internal combustion motor 21. The internal combustion motor 21, is of usual construction, of any desired design and construction, preferably of the four cycle type, of one or more cylinders.

- 40 The bars 10 and 11 are provided with pins 23, or extended elements, extended angularly therefrom, in one common direction. At the front of the lazy tong structure there are short bars 10^a and 11^a pivotally connected to each other at their front tips as at 24 and at the rear of the lazy tongue structure bars 10 and 11 are left with free rear extremities 25 and 26.

45 The above described construction is such as will permit the lazy tong to be opened or closed, horizontally, when the internal combustion motor 21 is operated, so as to cause the pins 23, to propel or drive the boat to which my improved device is attached. The 50 propelling cycle is accomplished by the closing or depressing of the said lazy tong.

The motor 27 is mounted on the platform 28. The wheels 29 are secured to the axles 30, rotatively mounted on the brackets 31 extended downwardly from the platform 28. 60 The wheels 29 are mounted on the tracks 32, secured to the said base 14. The above described construction is such as will permit the motor 21, to be positioned so as to allow the rod 18, to be extended at a right angle 65 to the lazy tong member, from the pin 16, as shown in Fig. 1 or permit the said rod 18, to be similarly extended from a similar pin not shown in the accompanying drawing, secured to the free rear extremity 25 of the 70 lazy tong, positioned in the aperture 34 formed therein. The latter described construction is such as will permit the lazy tong to be operated from the rear portion thereof.

The rod 35, is secured to the platform 28 75 and is extended downwardly therefrom through an elongated aperture 36, formed in the base 14. The hand wheel 37, is threadedly attached to the extended extremity of the rod 35, and is adapted to engage the base 80 14, so as to hold the motor 21 in the above described desired position.

Having thus described my invention, what I claim as new and desire to protect by Letters Patent of the United States is as follows:

1. In a propulsion device of the class described, an internal combustion engine mounted on a platform, wheels secured to the said platform, said wheels adapted to engage tracks secured to a base, a lazy tong pivotally attached, at its center to a bracket secured to the said base, a rod pivotally attached to the opposite center portion of the said lazy tong, said rod being pivotally attached to an eccentric pin secured to the rim 95 of the fly wheel of the said internal combustion motor.

2. In a propulsion device of the class described, an internal combustion engine mounted on a platform, wheels secured to the said platform, said wheels adapted to engage tracks secured to a base, a lazy tong attached at its center to a bracket secured to the said base, a rod pivotally attached to the opposite center portion of the said lazy 105 tong, said rod being pivotally attached to an eccentric pin secured to the rim of the fly wheel of the said internal combustion motor.

3. In a propulsion device of the class 110 described, an internal combustion engine mounted on a platform, wheels secured to

the said platform, said wheels adapted to engage tracks secured to a base, a lazy tong pivotally attached at its center to a bracket secured to the said base, a pin pivotally attached to the opposite center portion of the

5 said lazy tong, a rod pivotally attached to the pin, said rod being pivotally attached to

an eccentric pin secured to the rim of the fly wheel of the said internal combustion motor.

10 In testimony whereof I have affixed my signature.

WALENTY FILA.
